CLAIM

The ornamental design for a venturi fitting, as shown and described.

DESCRIPTION

FIG. 1 is a front view of a venturi fitting showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof; and,

FIG. 8 is a second perspective view thereof.

The broken lines seen in the drawings are for the purpose of showing environmental structure, and form no part of the claimed design.
